UNITED STATES PATENT OFFICE.

BERNARD D. WILLIS, OF CHICAGO, ILLINOIS, ASSIGNOR, BY MESNE ASSIGNMENTS, TO
FIRST TRUST AND SAVINGS BANK, TRUSTEE, OF CHICAGO, ILLINOIS.

TELEPHONE APPARATUS.

1,175,896.

Specification of Letters Patent. Patented Mar. 14, 1916.

Application filed October 5, 1906. Serial No. 337,593.

To all whom it may concern:

Be it known that I, BERNARD D. WILLIS, a citizen of the United States of America, and resident of Chicago, Cook county, Illinois, have invented a certain new and useful Improvement in Telephone Apparatus, of which the following is a specification.

My invention relates to telephone systems in general, but more particularly to automatic or semi-automatic telephone exchange systems, and especially to systems in which the automatic trunking or other switching is accomplished by selectors or connectors operating on the step-by-step principle.

Generally stated the object of my invention is the provision of improved means for enabling a calling subscriber to obtain connection with an operator or an attendant at the exchange or central station.

Special objects of my invention are the provision of improved means for enabling a calling subscriber of an automatic or semi-automatic telephone exchange to attract the attention of and secure telephonic communication with a central station operator or attendant; the provision of means whereby, out of a plurality of lines each provided with one or more telephones, the first idle line may be automatically selected by a calling subscriber whose telephone receives talking current from a common battery at the exchange or central station; and the provision of certain details and features of improvement and combinations tending to increase the general efficiency and improve the service of a telephone exchange system.

To the foregoing and other useful ends, my invention consists in matters hereinafter set forth and claimed.

In the accompanying drawings, Figure 1 is a diagram showing a subscriber's automatic substation at A, a central battery at B having its positive terminal preferably grounded at G. C indicates the well-known first-selector switch of an automatic exchange. At D is shown the relay and circuit connections of my improved signal-receiving apparatus. The substation A has operated the first-selector C, which latter in turn has selected a line of which D is a part. The apparatus at D is shown in an operated position, the key E having been thrown and the attendant's secondary circuit bridged across the line.

Fig. 2 is a diagram showing the trunk

line extended from the first operator's position to the second operator's position by throwing the key F. The attendant at the second position, in like manner, and by throwing the key H, may in turn extend the trunk line to the third position; thus when the trunk line is seized the signal will be transferred to position #3 without signaling positions #1 and #2.

For convenience of explanation, assume that in an automatic exchange the naught-level of ten contacts is connected with trunk lines leading to a tollboard, and that the tollboard terminal of each of said trunk lines is provided with one of my improved signaling arrangements. The operation of the signaling equipment, as used in this connection, is illustrative of its action in any connection in which it may be used.

The substation A may be of any suitable or approved type. The substation A comprises a receiver 2, switch-hook 3, induction-coil 4 which consists of the primary winding 5 and secondary winding 6, transmitter 7, condenser 8, ringer 9, impulse wheel 10 which has the usual vertical impulse teeth 11 that are adapted to operate the vertical impulse spring 12. The impulse wheel carries the rotary impulse tooth 13, which latter operates the rotary impulse spring 14. The switch-hook has radiating from its body a number of cam-arms 15, 16 and 17, and is pivotally secured to the key board (not shown) by the screw 18 about which it moves when the receiver is removed. The movement is produced by a spring (not shown), and the switch-hook is pushed up for the purpose of changing certain circuit connections to be disclosed. The cam-arm 15 controls the so-called locking arm 19. After the dial is rotated the locking arm 19 occupies the position shown at substation A. The mechanical operations by which this is brought about are well known. The co-operating ground springs 20 and 21 engage, thus placing the ground post 22 in contact with the substation ground G¹, whereby when the subscriber releases the dial for rotating it, as described, the vertical impulse teeth 11 will cause the vertical impulse spring 12 to come in contact with the ground post 22, and immediately following the rotary impulse tooth 13 causes the rotary impulse spring 14 to come in contact with the same ground post 22. When the switch-hook

is down the cam-arm 17 maintains a contact between the springs 23 and 24, thereby bridging the condenser 8 in series with the ringer 9 across the line. The springs 25 and 26 are then disengaged, and the primary circuit including the winding 5 in series with the transmitter 7 is interrupted by the separation of the springs 25 and 26.

The signaling device whereby a subscriber 10 may signal another subscriber after a connection has been established comprises a push button 28 and a spring 29, which latter normally engages the contact point 30; but when the push button 28 is pressed the 15 spring 29 leaves the contact point 30 and engages the contact point 31, which latter is connected with the substation ground G¹. The means whereby the subscriber may release the central station apparatus brought 20 into service comprises three springs 32, 33 and 34 known as the release-springs and so controlled by the cam-arm 16 that when the switch-hook descends the three release-springs are brought into contact, thereby 25 grounding both the subscriber's line conductors simultaneously.

The first-selector switch shown at C may be of any suitable or approved type, for instance of the general type described in Patent No. 815,321, issued March 13, 1906, to 30 Keith, Erickson and Erickson. It embodies among other details the following well-known devices and circuits: A switch-shaft (not shown) carries the vertical and rotary 35 wipers 39 and 40, respectively, and the private wiper 41. The side switch is well known and comprises the side switch wipers 42, 43, 44 and 45, which may be designated as vertical, rotary and private side switch 40 wipers and the rotary magnet side switch wiper, respectively. The side switch is under the control of the private magnet 46. Through the medium of the vertical line relay 47, and while the side switch is in first 45 position, the subscriber controls the vertical magnet 48, which latter operates to raise the shaft and shaft wipers 39, 40 and 41 vertically. By means of the rotary line relay 49, and while the side switch is in first or second 50 position, the subscriber controls the private magnet 46 and, therefore, the side switch. While the side switch is in second position the rotary magnet 50, which carries the shaft and shaft wipers in a rotary or circular 55 direction, is energized. The vertical and rotary line relays 47 and 49 acting conjointly provide means whereby the subscriber controls the release magnet 51 while the side switch is in first or second position. After the side switch passes to third 60 position, then, since the first-selector is of the trunk-release type, the said switch is controlled through the next switch with which a connection has been established, 65 through the private wiper 41 and by means

of the back-release relay 52. The bridge-cut-off-relay 53 is provided to open the connection between the line relays 47 and 49 and between said relays and battery B. This is desirable, because if the relays are 70 not disconnected from each other, and from the battery, the ringing current for signaling the subscriber may operate either or both of the relays 47 and 49, moving the selector switch C off normal. It is also desirable to remove the bridge formed through the said relays from across the line to give the voice-currents as clear a path as possible. The first-selector switch-shaft is also provided with a normal post arm 54 which, 75 when the shaft is in normal position, closes the spring 55 in contact with the contact point 56; but when the shaft is raised one or more steps the spring 55 closes in contact with the contact point 57, by which switching means the switch is made busy while off normal, and the energizing circuit for the relay 53 is controlled.

My improved apparatus comprises a vertical relay 58, a rotary relay 59 having two 90 windings 60 and 61, releasing relay 62 which releases the rotary relay 59 when the latter has become locked by an energizing circuit through the winding 60. Through the differential relay 63 the calling substation is 95 provided with talking battery current when the operator's key E is thrown to listening position. The rotary line receives current from the non-grounded pole of the battery through the winding 64, and the vertical 100 line receives current from the grounded pole of the battery through the winding 65 of the differential relay 63. The lamp relay 66 is provided for closing an energizing circuit through the signal lamp 67. When the key E is in the operated position shown in Fig. 1 the springs 68 and 69, and 70 and 71 are pressed into contact, thus bridging the operator's receiver set across the trunk line by way of the condensers 72 and 73. 110 The operation of the key also causes the spring 74 to pass from engagement with the spring 75 into engagement with the spring 76, and the springs 77 and 78 to disengage.

To establish connection with the tollboard operator the subscriber A removes the receiver 2 from the switch-hook 3, which latter separates the springs 23 and 24, thereby removing the ringer from across the line and substituting therefor the primary circuit by permitting the springs 25 and 26 to close. Since the trunk lines lead off from the naught-level of the first-selectors, the subscriber suitably operates his dial for the 120 125 digit 0, thereby grounding the vertical line conductor 79 ten times, and the rotary line conductor 80 once upon the return motion of the dial. The ground post 22 is placed in connection with the substation ground G¹. 130

in the well-known and familiar manner. Grounding the vertical line conductor 79 ten times energizes the vertical line relay 47 of the first-selector. The circuit through said relay extends from ground G^1 through the springs 20 and 21, vertical impulse spring 12, vertical line conductor 79, side switch wiper 42, contact point 81, through the winding of the vertical line relay 47, bridge-cut-off springs 82 and 83 to the battery lead 84, thence through battery B to ground G. Each time the vertical line relay 47 is energized the springs 85 and 86 are pressed into engagement and an energizing circuit is established each time through the vertical magnet 48. The circuit through the said magnet extends from ground G^2 to the springs 85 and 86, to the private magnet springs 87 and 88, vertical magnet 48 to the battery lead 84, thence through battery B to ground G. The vertical magnet being operated ten times the first-selector switch-shaft and wipers 39, 40 and 41 are carried to a level with the contact points that constitute the terminals of the trunk line leading to the circuit D. Following the vertical impulses the rotary impulse spring comes in contact with the ground post 22, thereby grounding the rotary line conductor 80 once and energizing the rotary line relay 49 of the first-selector once. The path of the energizing current may be traced as follows: from the substation ground G^1 to the rotary line conductor 80, side switch wiper 43, contact point 89 to the rotary line relay 49, bridge-cut-off springs 90, 82 and 83 to the battery lead 84, thence through battery B to ground G. The rotary line relay 49 upon energizing closes in contact the springs 91 and 85, thereby closing an energizing circuit through the private magnet 46 which extends from ground G^2 to the springs 85 and 91, private magnet 46 to the battery lead 84, thence through battery B to ground G. The private magnet 46 being energized for a moment the side switch of the first-selector C passes from first to second position, thereby permitting the side switch wiper 45 to engage the contact point 92, thus closing a circuit through the rotary magnet 50. The current flow is from the ground G^3 to the contact point 92, side switch wiper 45, interrupter springs 93 and 94, through the winding of the coil of the rotary magnet 50, thence to the battery lead 84, and through battery B to ground G. The rotary magnet is energized one step and the shaft wipers 39, 40 and 41 are carried into engagement with the bank contacts that constitute the terminals of a trunk line leading to the circuit D. Assume that the trunk leading to the said circuit leads off from the first set of contacts of the naught-level. If the first trunk line is busy an energizing circuit is established through the private magnet 46 when

the private wiper 41 strikes the busy private bank contact, which is, of course, grounded, thereby retaining the side switch in second position and maintaining the energizing circuit through the rotary magnet 50. The rotary magnet by intermittent magnetization thus causes the shaft to rotate step-by-step and carry the wipers past the last busy trunk line. However, as soon as the private magnet is deenergized the side switch is tripped into third position; but if there are no busy contacts to be passed over, as assumed in the first instance, the rotary magnet 50, as is well known, trips the side switch to third position, with the result that the side switch wipers 42, 43, 44 and 45 engage their respective contact points 95, 96, 97 and 98, thus extending the subscriber's line conductors 79 and 80 to the attendant's circuit D. Also, since the side switch wiper 44 engages the ground contact point 97, a guarding potential is established at the private wiper 41 for protecting the seized line from being molested by any other switch. When the side switch wiper 44 passes to the ground contact point 97 an energizing circuit is established through the lamp relay 66. Said circuit extends from ground G^4 to contact point 97, side switch wiper 44, release relay 52, switch-shaft private wiper 41, contact point 99, relay armature 100, through the winding of the lamp relay 66, contact point 101, relay armature 102, battery lead 84, thence through battery B to ground G. The lamp relay 66 upon energization closes a circuit through the signal lamp 67. This circuit extends from ground G^5 to the springs 78 and 77, relay armature 103, contact point 104, signal lamp 67 to the battery lead 84, thence through battery B to ground G.

The operator in response to the signal throws the key E to the position shown in Fig. 1. This results in breaking, at the springs 77 and 78, the circuit through the signal lamp, and placing in contact the springs 68 and 69 and 70 and 71, which bridges the operator's set across the said line, and furthermore the spring 74 disengages from the spring 75 and comes in contact with the spring 76. This latter contact closes a circuit which supplies the calling substation with current for talking purposes. The circuit extends from ground G^6 through the winding 65 of the differential relay 63, contact point 105, relay armature 106, springs 76 and 74, through the winding of the vertical line relay 58, conductor 115, wiper 39, side switch wiper 42, vertical line conductor 79, springs 25 and 26, push button spring 29, contact point 30, transmitter 7, primary winding 5, rotary line conductor 80, side switch wiper 43, contact point 96, shaft wiper 40, conductor 116, through the winding 61 of the rotary relay 59, winding 64 of the differential relay 63 to the battery 120.

lead 84, thence through battery B to ground G. The talking current energizes the vertical relay 58, which latter attracts its armatures 107 and 108. The former closes in contact with the point 109, and the latter (108) closes in contact with the contact point 110. The talking current in passing through the winding 61 of the rotary relay 59 energizes said relay, and the armature 100 is drawn from in contact with the point 99, thereby breaking the energizing circuit extending from ground G¹ through the lamp relay 66 and to battery B. The armature 111 engages the point 112, which establishes an energizing circuit through the winding 60. Said circuit locks the relay 59 in an operated position until the said circuit is broken at the contact point 113 and armature 114. This locking circuit extends from ground G¹ to armature 114, contact points 113 and 112, armature 111, through the winding 60 to battery lead 84, thence through battery B to ground G. Since both windings 64 and 65 of the relay 63 are differentially arranged, the relay armatures 102 and 106 remain in their normal positions, even though current is flowing through both windings. Suppose the subscriber A has delivered the message to the operator and the operator has restored the key E to normal position, as shown at E in Fig. 2, thus removing the talking circuit to substation A and restoring the relays, except the double-wound relay 59, which is maintained energized by the locking circuit previously traced. In the meantime the subscriber at A has not replaced the receiver on the switch-hook, but desires to add to the message. Accordingly the signaling button 28 is pressed, grounding the vertical line conductor 79, which causes the signal lamp 67 to flash. The circuits established in bringing this about are as follows: from substation ground G¹, contact point 31, spring 29, springs 26 and 25, vertical line conductor 79, side switch wiper 42, contact point 95, shaft wiper 39, conductor 115, through the winding of relay 58, springs 74 and 75 to the battery lead 84, thence through battery B to ground G. The vertical relay 58 upon energizing attracts the armatures 107 and 108, which latter closes an energizing circuit through the lamp relay 66, which in turn attracts its armature 103 and establishes a circuit through the signal lamp 67, as previously traced. The operator in response again throws the key E, switching the springs allotted thereto as explained. The release of the signaling apparatus when the key E is in normal position is brought about when the subscriber A restores the receiver 2 to the switch-hook 3 and simultaneously grounds both the vertical and rotary line conductors 79 and 80, respectively. This results in a flow of current from substation ground G¹ to the release-springs 32, 33 and 34, thence over the conductor 79, through the line relay 58, springs 74 and 75 to battery B and to ground G, as previously traced. The current flow over the rotary line extends from substation ground G¹ to the release-springs 32 and 33, rotary line conductor 80, thence through the relays 59 and 63, as previously followed, to battery B and to ground G, energizing the differential relay 63. The energization of the vertical relay 58 closes in contact the armature 107 and the contact point 109, which places the release relay 52 of the first-selector in series with the release-relay 62 of the signaling apparatus. The current that passes through the winding 64 of the differential relay 63 magnetizes the core, which attracts the armature 102 and places in contact the said armature and contact point 117, thereby establishing an energizing circuit through the said release relays. This circuit extends from ground G¹, contact point 97, side switch wiper 44, through the winding of the release relay 52, switch-shaft wiper 41 to the armature 107, contact point 109, through the winding of the release relay 62, contact point 117, armature 102 to the battery lead 84, thence through battery B to ground G. The energization of the release relay 62 causes the armature 114 to disengage from the contact point 113, thereby opening the locking circuit through the winding 60 of the rotary relay 59. The release relay 52 of the first-selector upon energization places in contact the springs 118 and 119, which in turn completes an energizing circuit through the release magnet 51 extending from ground G¹ to the springs 118 and 119, release magnet 51 to the battery lead 84, thence through battery B to ground G. The release relays and magnet thus energized attract their respective armatures, and as soon as the substation release springs 32, 33 and 34 separate and break the ground connection with the line conductors 79 and 80 they again de-energize, releasing all apparatus brought into service by the calling subscriber. Assume that the calling subscriber A replaces the receiver before the key E is restored. The release is then brought about over slightly different circuits. The differential relay 63 has current flowing in both windings 64 and 65, and now when the release springs are brought into contact the winding 65 of the relay 63 is short-circuited as follows: from ground G¹, winding 65, contact point 105, armature 106, springs 76 and 74, relay 58, thence to the vertical line conductor 79, release-springs 34, 33 and 32 to the substation ground G¹. Since the winding 64 alone carries current the relay 63 becomes active and closes in contact the armature 102 and contact point 117 and the

armature 106 and contact point 120. The vertical relay 58 now becomes energized by a current flowing from the substation ground G^1 , vertical line conductor 79 to the relay 58, springs 74 and 76, armature 106, contact point 120 to the battery lead 84, thence through battery B to ground G. The armature 102 upon engaging the contact point 117 completes the energizing circuit through the release relays 52 and 62, and, as previously described, the selector C is released after the release-springs 32, 33 and 34 separate; the connection to the circuit D is broken; the relay 59 is deenergized, and all 15 energized parts are fully restored.

In a system of great size where the switches are divided into groups, from every group there will lead off, of course, ten trunk lines to the board in which all switching circuits are located. The arrangement may be such that all the trunk lines terminate at one operator's position, or if the traffic becomes heavy, additional operators' 20 positions may be provided, as shown in Fig. 2.

When this arrangement is followed out it is sometimes desirable to transfer all the calls to one operator's position, for instance at night time. The work being slack at night one operator may be able to take care 25 of all the work, or two operators, etc., as is well known. Such an arrangement may be accomplished with the provision of circuits disclosed in Fig. 2. Each trunk line instead of being provided with only one key 30 E may be provided in addition with multiple keys F and H, as indicated. Each of the said keys F and H has a left-hand section which is an exact duplicate of the key E, and in addition a right-hand section 35 whereby the work may be transferred from one operator's position to the next. Normally the keys F and H rest in the position indicated at H. If the key is thrown in one 40 direction, the right-hand set of springs is switched as shown at F, and if switched in the reverse direction the left-hand set of springs is operated, as shown at E, Fig. 1. If the operator at position #1 (Fig. 2) wishes to transfer all calls coming over the 45 trunk line conductors 115 and 116, the key F is then thrown so that the right-hand set of springs is operated as shown in Fig. 2, whereby the incoming signals will appear at a second attendant's lamp and thus relieve the first operator; likewise the second attendant may transfer the incoming signals to a third operator, etc. In Fig. 2 the key F is shown operated in such manner as to transfer the signal to the lamp 121 50 at position #2. The relay 66 upon energization places in contact the armature 103 and contact point 104, which closes a circuit through the signal lamp 121. Said circuit extends from ground G^1 to the springs 78 55 and 77 of the key E, springs 124 and 125

of the key H, springs 126 and 127 of the key F, armature 103, contact point 104, springs 128 and 129 of the key F to the springs 130 and 131 of the key H, through the signal lamp 121 to the battery lead 84, 70 thence through battery B to ground G. The operator in response to the signal throws the key H, operating the springs at the left. This results in breaking the circuit at the springs 124 and 125 through 75 the signal lamp and placing in contact the springs 132 and 133 and 134 and 135, which bridges across the said trunk line the operator's set; and furthermore, the spring 136 disengages from the spring 137 and 80 comes in contact with the spring 138. This latter contact closes the circuit which supplies the calling substation with battery current for talking purposes. The circuit extends from ground G^1 through the winding 85 65 of the differential relay 63, contact point 105, relay armature 106, springs 138 and 136 and springs 139 and 140 of the key H to the springs 141 and 142 of the key F, through the winding of the vertical line 90 relay 58, thence over the circuit as previously traced to the battery B and to ground G. The talking current energizes the vertical relay 58, which latter operates with known results. 95

The release of the signaling apparatus when the key H is in normal position is brought about when the subscriber A restores the receiver 2 to the switch-hook 3 and simultaneously grounds both the vertical and rotary line conductors 79 and 80, respectively. This results in a flow of current from the substation ground G^1 to the release-springs 32, 33 and 34, thence over the conductor 79, through the line relay 58, 100 springs 142 and 141 of the key F, springs 140 and 139 and 136 and 137 of the key H to the battery lead 84, thence to battery B and to ground G. The current flow over the rotary line has already been traced. 105 The energization of the vertical relay 58 closes in contact the armature 107 and the contact point 109, which places the release relay 52 of the first-selector in series with the release relay 62 of the signaling apparatus, with the result that the said signaling apparatus and first-selector are released and fully restored, as previously described. 110 Thus it will be seen that when the keys E, F and H are in normal position all of the 115 incoming calls over the trunk conductors 115 and 116 are received by the first operator, and when the key F is operated, as shown in Fig. 2, and the keys H and E remain at normal, the incoming calls are transferred 120 from the first operator's position to the second operator's position; likewise, when the key H is thrown, operating the springs on the right, the key F remains as shown, and then the incoming signals pass from 125 130

the first and second positions to the third operator's position. Furthermore, it will be noticed that the spring combination of the left side of the keys F and H is exactly like the spring combination of key E. The springs 69 and 70 of the key E, like the corresponding springs 133 and 134, and 143 and 144 of the keys H and F, respectively, are connected directly with the conductors 122 and 123. The springs 68 and 71 of the key E connect with the operator's set; also the similar springs 132 and 135 and 145 and 146 of their respective keys H and F connect with the operator's set of their respective positions. The spring 75 and the corresponding springs 137 and 146 of the keys H and F, respectively, are connected with the battery lead 84. The spring 74 (Fig. 1) connects with the vertical relay 58; but in Fig. 2 the connection with the said relay is from the spring 74 to the springs 147 and 140, when the key is thrown and the right-hand set of springs is operated, and to springs 141 and 142 of the key F and to the vertical relay 58. The corresponding spring 136 of the key H connects with the same relay through the springs 139 and 140 of the key H, springs 141 and 142 of key F to the vertical relay 58. Also, the corresponding spring 148 of the key F connects with the said relay through the springs 149 and 142 when the key F is in normal position. The spring 76 and the corresponding springs 138 and 150 of the keys H and F, respectively, are connected with the armature 106. In Fig. 1 the springs 77 and 78 are connected in series between the armature 103 and ground G⁵; but in Fig. 2 the corresponding springs 125 and 124, and 127 and 126, respectively, are included in series with the springs 77 and 78 in the circuit from the armature 103 to ground G⁵.

The relays may be of any suitable resistance, but it has been found that good results are obtained when the relays are wound to the following resistances: vertical relay 58 one hundred and fifty ohms; release relay 62 forty-five ohms; lamp relay 66 five hundred ohms; windings 60 and 61 one hundred and fifty ohms; the windings 64 and 65 of the differential relay 63 two hundred and fifty ohms each.

From the foregoing it will be evident that my new signaling apparatus and circuit may be applied to any line over which a call or signal is received.

From the foregoing it will be seen that one or more operators' or attendants' telephones can be located on one line, and that such line is in the nature of a telephone line, inasmuch as it leads directly to a telephone or telephones. In such case means are provided, as explained, for enabling a calling subscriber whose telephone receives talking current from the exchange or cen-

tral station to automatically select the first idle one of said telephone lines. If these special lines for the operators or attendants lead from a certain level of the first-selector, then the other levels may be devoted to regular service—that is to say, they may have ordinary trunk lines leading therefrom. For the broader purposes of my invention, however, it is not necessary that these special lines for the operators' or attendants' telephones lead from the first-selector, as they may lead from any other suitable automatic selective switch. The springs 126 and 127, 124 and 125, and 77 and 78 produce additional breaks in the circuits of the operators' or attendants' signaling lamps, so that these lamps will be extinguished by the operation of the keys, since the signal relay 66 is retained energized even after the operator throws her key. As shown, and for the more specific purposes of my invention, these special telephone lines for the operators or attendants are in the nature of one-way lines—that is to say, they are adapted for calling only in one direction. In other words, they are adapted only for the transmission of incoming calls, and not for the transmission of outgoing calls. In this way each operator or attendant can receive calls over these special lines, but cannot transmit any calls over the same in the opposite direction. When an operator or attendant receives instructions from a calling subscriber, long distance connection can then be made or trouble reported, according to the duties of the attendant receiving the message from the calling subscriber. Obviously, all ten contacts in any certain level—say the tenth level—of a selector can be appropriated for special service in calling operators or attendants at the exchange or central station, so that each operator can supervise all ten of the special telephone lines. Of course, if there should be ten groups of selectors the same operator can superintend the ten circuits from each of the ten groups, or one hundred circuits in all. Evidently when one hundred circuits are too much for one operator any number of them may be transferred to another operator, as explained. If desired these special telephone lines could be extended to another station or exchange to enable a calling subscriber of one exchange to directly call an operator or attendant at the other exchange. Obviously, many other uses of my invention will suggest themselves to those skilled in the art in addition to those which I have mentioned.

As explained, special service lines or circuits are provided for the operators' or attendants' telephones, each line or circuit comprising three conductors, the third conductor being used for a leasing purposes, as

well as for inclusion in the energizing circuit of the relay which controls the line lamp signals associated with the operators' telephones. During conversation it will be seen

5 that the common battery or centralized source of operating and talking current is bridged across the special service line or circuit through the medium of relay-coils associated with said special service line or 10 circuit. In this way current for talking purposes is supplied over the special service line or circuit to the calling subscriber's line.

What I claim as my invention is:—

15 1. In a telephone exchange system, the combination of a line, a plurality of operators' or attendants' telephones on said line, a visual signal for each telephone, a calling subscriber's line, automatic means for connecting the calling line with the other said line, parallel circuits for said visual signals, relay means controlling said circuits, means by which one operator or attendant may direct the incoming calls to the visual signal 20 of the next operator, and means for supplying talking current over a portion of said first line to the calling subscriber's line.

25 2. In a telephone exchange system, the combination of a line, a plurality of operators' or attendants' telephones on said line, a call-receiving device for each telephone, a calling subscriber's line, automatic means for connecting the calling line with the said other line, means by which one operator may disconnect from the line and direct all incoming calls to the next operator, and means for supplying talking current over a portion of said first line to the calling subscriber's line.

30 3. In a telephone exchange system, the combination of a calling subscriber's line, a special service line, a telephone on said special service line, a call signal for said telephone, trunk lines for regular service, 35 automatic means for connecting the calling line with the special service line, and means for supplying talking current over a portion of the special service line to the calling subscriber's line.

40 4. In a telephone exchange system, the combination of a calling subscriber's line, trunk lines for regular service, a plurality of special service lines, telephones on said special service lines, an automatic selector-switch adapted to establish connection with the first idle one of said special service lines, or with the first idle trunk line when used for regular service, a centralized source of talking and operating current, connections for supplying operating current from the said source to the said selector-switch, and means for bridging the said source across the automatically selected special service line to supply talking current to the calling subscriber's line.

5. In a telephone exchange system, the combination of a calling subscriber's line, a special service line, automatic means for connecting the calling line with the special service line, a telephone on said special service line, a visual signal associated with said telephone, a listening-key for connecting the telephone with the special service line, a circuit for said visual signal, a relay for controlling said circuit, an energizing circuit for said relay, a second relay for controlling said energizing circuit, and a local locking circuit for said second relay.

6. In a telephone exchange system, the combination of a calling subscriber's line, a special service line, automatic means for connecting the calling line with the special service line, a telephone on said special service line, a visual signal associated with said telephone, a listening-key for connecting the telephone with the special service line, a circuit for said visual signal, a relay for controlling said circuit, an energizing circuit for said relay, a second relay for controlling said energizing circuit, a local locking circuit for said second relay, a third relay controlling said local circuit, an energizing circuit for said third relay, and two additional relays controlling the circuit of said third relay, said locking circuit being 90 also controlled by the second relay itself.

7. In a telephone exchange system, the combination of a calling subscriber's line, a special service line, automatic means for connecting the calling line with the special service line, a telephone on said special service line, a visual signal associated with said telephone, a listening-key for connecting the telephone with the special service line, a circuit for said visual signal, a relay for controlling said circuit, an energizing circuit for said relay, a second relay for controlling said energizing circuit, a local locking circuit for said second relay, a third relay controlling said local circuit, an energizing circuit for said third relay, and two additional relays controlling the circuit of said third relay, said locking circuit being also controlled by the second relay itself, the said first-mentioned relay having another energizing circuit controlled by the two additional relays.

8. A telephone exchange system provided with a line, an operator's or attendant's telephone on said line, a visual signal associated with said telephone, suitable means by which a calling subscriber may make connection with said line, a circuit for said visual signal, a relay controlling said circuit, two energizing circuits for said relay, a relay controlling one energizing circuit, 120 and another relay controlling the other energizing circuit.

9. A telephone exchange system provided with a line, an operator's or attendant's tele- 125

- phone on said line, a visual call-signal associated with said telephone, a key-switch for connecting the telephone with the line, suitable means by which a calling subscriber connects himself with said line and causes the display of said signal, means for restoring said signal upon the actuation of said key-switch to connect the telephone with the line, and automatic means for then preventing a display of said signal when the operator restores the key to normal position.
10. In a telephone exchange system, an operator's or attendant's telephone, a visual signal associated with said telephone, means for operating said signal to cause a display thereof, a key-switch provided with means for retiring said signal, when the telephone is brought into use, and relay means for preventing a display of said signal when the key-switch is restored to normal position.
15. In a telephone exchange system, the combination of a line, a calling subscriber's line, automatic means by which the calling subscriber connects his line with the said first-mentioned line, a plurality of operator's telephones on said first-mentioned line, a call-signal associated with each telephone, means by which one operator may direct the 20 incoming automatic calls to the next operator, and means for supplying talking current over a portion of said first line to the calling subscriber's line.
25. In a telephone exchange system, the combination of a calling subscriber's line, a special service line, a subscriber's individual switch for automatically establishing connection with said line, trunks for regular service also leading from said individual switch, a telephone on said special service line, a call-signal associated with said telephone, and means including a relay for automatically causing the display of said signal when the individual switch establishes 30 connection with the said special service line.
35. In a telephone exchange system, the combination of trunk lines for regular service, a plurality of special service lines, which lines are not available for service between other lines, an automatic selector-switch having a bank of contacts or terminals in which all of said lines terminate, telephones on said special service lines, call-signals associated with said telephones, automatic 35 means for causing the operation of a call-signal when the selector establishes connection with a special service line, a calling subscriber's line, and means for enabling the calling subscriber to start the operation of the selector, said selector provided with automatic means for causing it to stop or come to rest on the first idle trunk line, or on the first idle special service line, according to the character of the call.
40. In a telephone exchange system, the combination of a calling subscriber's line, a one-way special service line adapted for calling only in one direction, which special service line is not available for service between other lines, a telephone on said special service line, a call-signal associated with said telephone, subscriber-controlled automatic means by which connection is established between the subscriber's line and the special service line, automatic means for causing the operation of said signal when connection is made with the special service line, an impulse-transmitting mechanism for the calling line, adapted to control said means for connecting with the trunk, and a hook-switch on the calling line but separate from said mechanism.
45. In a telephone exchange system, the combination of a plurality of lines, telephones for said lines, operators' key-switches for connecting said telephones with said lines, a visual signal associated with each telephone, relays controlling each signal, a calling subscriber's line, means for automatically placing the calling line in connection with an idle one of said plurality of lines, means controlled by one of said relays for automatically operating the visual signal of one of said telephones when such a connection is established, means controlled by another of said relays for rendering said signal inoperative, and means for supplying talking current over the called line to the subscriber's telephone.
50. In a telephone exchange system, the combination of a calling subscriber's line, trunk lines for regular service, a plurality of special service lines, telephones on said special service lines, an automatic selector-switch adapted to establish connection with an idle one of said special service lines, or with an idle trunk line when used for regular service, a centralized source of talking and operating current, connections for supplying operating current from the said source to the said selector-switch, and means for bridging the said source across the automatically selected special service line to supply talking current to the calling subscriber's line.
55. In a telephone exchange system, the combination of a line having a third conductor, a telephone on said line, automatic switching means for establishing connection with said line, release mechanism for said automatic switching means, a release-circuit including said third conductor, and means allotted to said line and adapted for controlling said release circuit.
60. In a telephone exchange system, the combination of a line having a third conductor, a telephone on said line, automatic switching means for establishing connection with said line, release mechanism for said automatic switching means, a release-circuit including said third conductor, and means allotted to said line and adapted for controlling said release circuit.
65. In a telephone exchange system, the combination of a line having a third conductor, a telephone on said line, automatic switching means for establishing connection with said line, release mechanism for said automatic switching means, a release-circuit including said third conductor, and means allotted to said line and adapted for controlling said release circuit.

- with said line, release mechanism for said automatic switching means, a release circuit including said third conductor, and relays allotted to said line and controlling normally open switch points in said circuit. 5 to rest on an idle trunk line, or on an idle 60 special service line, according to the character of the call.
19. In a telephone exchange system, the combination of a line having three conductors, automatic means for establishing connection with said line, release mechanism 10 for said automatic means, a release circuit including the third conductor of the line, a telephone allotted to said line, means for connecting the telephone with the two main conductors of said line, and relay means 15 allotted to said line and controlling the said release circuit.
20. In a telephone exchange system, the combination of trunk lines for regular service, a plurality of special service lines or 20 circuits, a calling subscriber's line, automatic means by which the calling subscriber selects an idle special service line or circuit, or an idle trunk line, release mechanism for said automatic means, means allotted to said 25 special service lines or circuits and adapted for controlling said release mechanism, telephones on said special service lines or circuits, a signal for each telephone, and a common battery or centralized source of current 30 for furnishing current to the calling subscriber's line for talking and signaling purposes.
21. In a telephone exchange system, the combination of a calling subscriber's line, 35 another line, a telephone, a common battery, automatic means for establishing connection from the calling line to the said other line, operator's switching means for connecting said telephone with said other line, said 40 means including an operator's listening-key having provisions for establishing the flow of talking current to the calling subscriber's line when the operator listens-in.
22. In a telephone exchange system, the 45 combination of trunk lines for regular service, a plurality of special service lines, which lines are not available for service between other lines, an automatic selector-switch having a bank of contacts or terminals in which all of said lines terminate, telephones on said special service lines, call-signals associated with said telephones, automatic means for causing the operation of a call-signal when the selector establishes 50 connection with a special service line, a calling subscriber's line, means for enabling the calling subscriber to start the operation of the selector, said selector provided with automatic means for causing it to stop or come
- to rest on an idle trunk line, or on an idle 60 special service line, according to the character of the call.
23. In a telephone system, a line having a third conductor, a bridge on said line, a switch for making connection to said line, 65 responsive to the calling subscriber, means in said bridge responsive to the calling subscriber for releasing said switch over the third conductor, and a telephone for said line. 70
24. In a telephone system, a line, a relay bridge on said line, means for extending a call to said line, a telephone for said line, means for supplying talking current over said bridge and line in the direction of the 75 calling subscriber, a signal at the telephone, and means controlled by the relay of said bridge responsive to the calling subscriber for controlling said signal.
25. In a telephone exchange system, the 80 combination of a line having a third conductor, a telephone on said line, a signal for said line controlled over said third conductor, automatic switching means for establishing a connection with said line, release 85 mechanism for said automatic switching means, a release circuit including said third conductor, and means allotted to said line and adapted for controlling said release circuit. 90
26. In a telephone exchange system, the combination of a line having a third conductor, a telephone on said line, a signal for said line controlled over said third conductor, a calling subscriber's line, automatic 95 switching means for establishing connection with said first line, release mechanism for said automatic switching means, a release circuit including said third conductor, and means allotted to said first line and adapted 100 for controlling said release circuit, said last means controlled over said calling line.
27. In a telephone system, a line having a third conductor, a signal for said line controlled over said third conductor, a bridge 105 on said line, a switch for making connection with said line responsive to the calling subscriber, means in said bridge responsive to the calling subscriber for releasing said switch over said third conductor, and a telephone for said line. 110

Signed by me at Chicago, Cook county, Illinois, this 28th day of September, 1906.
